UNITED STATES PATENT OFFICE.

CHESTER RAY HANNING, OF NORTH BEND, OREGON.

HACK-SAW FRAME.

Application filed July 30, 1926. Serial No. 126,084.

This invention relates to hacksaws and has for its object the provision of a novel hacksaw frame embodying means whereby a saw blade may be very quickly and easily placed in position or removed, as the case may be, and clamped securely with the proper degree of tension on the blade to insure efficient operation thereof.

An important object of the invention is to provide a hacksaw frame which is capable of holding hacksaw blades of different lengths, means being moreover provided whereby the necessary tension on the blade may be had regardless of the length thereof.

Another object of the invention is the provision of a hacksaw frame having its blade engaging elements so constructed or formed that a blade may be readily mounted for sawing in the same plane as the back or at right angles thereto.

A more specific object is the provision of a hacksaw frame having a back carrying an anchor member adjustable therealong for mounting one end of a saw blade, the frame having its handle end carrying a peculiarly constructed and mounted cam means for applying a longitudinal pull upon the blade so that it will be placed under tension, the action being a clamping one and being maintained without the employment of any auxiliary or extraneous securing means.

An additional object of the invention is to provide a device of this character which will be simple and inexpensive to manufacture, efficient in use, a great time and labor saver, durable in service, and a general improvement in the art.

With the above and other objects and advantages in view, the invention preferably consists in the combination and arrangement of parts and the structural features to be hereinafter more fully described, claimed and illustrated in the accompanying drawing, in which:—

Figure 1 is a side elevation of the complete hacksaw showing a blade in secured position.

Figure 2 is a fragmentary elevation of the handle end showing the blade holding means in released position.

Figure 3 is a longitudinal section through the handle end showing the blade holding means in operative position, the parts being in the same position as in Figure 1.

Figure 4 is an inverted edge view of the handle end with the blade omitted, and

Figure 5 is a detail perspective view of the longitudinally movable tension applying member.

Referring more particularly to the drawings, I have shown the stationary portion of the saw as comprising a back 10 formed as an elongated bar of suitable material and dimensions and preferably rectangular in cross section. This bar is straight throughout its major portion but has one end 11 curved and terminating in an extension 12 formed or otherwise provided with a guide sleeve 13 arranged in parallel relation to the back or bar 10 and having a preferably rectangular bore or opening 14 therethrough. The numeral 15 designates the handle which may be constructed of wood, as is generally customary, the handle being preferably slotted or bifurcated, as shown, so as to straddle the portion 11 of the frame, and rigid connection being effected by means of bolts, screws or other securing elements 16, it being understood, however, that such details as these may be readily varied within the scope of the invention.

Carried by the back or bar member 10 is the front anchor member designated as a whole by the numeral 17, this member being provided for the purpose of holding the forward end of the saw blade 18. The member 17 is represented as including an arm 19 having one end formed or otherwise provided with a yoke 20 slideable along the back or bar 10 so that the member 17 may be shifted bodily toward or from the handle depending upon the length of the saw blade to be used. The member 17 is intended to lock in position with respect to the back or bar 10 upon slight lateral rocking movement with respect thereto, and for this reason it is shown as equipped with a lateral projection or heel piece 21 adapted to bear against the inner or under edge of the back or bar 10. The end of the arm 19 remote from the bar 10 is provided with a lateral extension 22 which is preferably square in cross section and provided on each flat face with a pin or equivalent projection 23 upon which may be engaged the hole 24 commonly provided at one end of the hacksaw blade.

The means connected with the rear end of the blade for maintaining proper tension thereon comprises a pull bar 25 preferably square in cross section to prevent turning thereof and equipped on each face with a pin 26 upon which may be engaged the hole 27

at the rear end of the blade. In actual practice the members 22 and 25 are preferably similar and it will be quite apparent that there are four possible positions in which the 5 blade may be mounted, depending upon the nature of the work to be done. The member 25 slides through the square bore 14 in the sleeve or guide box 13 and has its rear portion preferably bifurcated at 28, a roller 29 10 being pivoted within the bifurcation.

Pivotal mounted in any suitable manner upon the extension 12, as shown at 30, is a loop-like hand-hold 31 constituting an actuating lever and movable within the space between the bar 10, the extension 12 and the end portion 11 and adapted to fit snugly against the inner or concave side of the latter when in blade holding position. The member 31 carries a curved finger 32 which 20 operates within the bifurcation 28 and in engagement with the roller 29 for the purpose of serving as a cam for moving the member 25 longitudinally and thereby controlling the tension on the blade. The location and shape of the curved finger 32 are such that when the hand-hold 31 is in its operative position as shown in Figures 1 and 3, the active surface 33 of the finger will engage the roller 29 at a point past center with 30 respect to the pivotal mounting of the hand-hold so that after the blade has been placed under tension the pull of the blade against the cam member 32 will act to hold the member 31 firmly against the inner edge of the end portion 11. The front portion of the loop shaped actuating lever 31 serves to protect the fingers of the operator, when the device is in use.

In the use of the device, it will be seen that the member 17 must be shifted along the back or bar 10 to a certain selected point depending upon the length of the saw blade 18 to be used. The forward end of the blade has the hole 24 engaged upon a selected one 45 of the pins or projections 23. The hand-hold 31 is then swung forwardly or away from the handle 15 into the position shown in Figure 2 and the hole 27 at the rear end of the blade is engaged upon the proper one 50 of the pins 26. The operator then may place the palm of his hand against the outer or rear surface of the handle and pass his fingers through the hand-hold or loop 31. By the simple act of closing the hand the member 31 will then be drawn toward and into engagement with the end portion 11 of the frame. When this is done the concave or active face 33 of the cam 32 will engage against the roller 29 and impart longitudinal movement to the member 25 and this will of course place the saw blade under tension. Whenever it is necessary to change a blade, 60 release is effected by forcing the member 31 forwardly into the position shown in Figure 2. Obviously this may be done very sim-

ply by pulling upon it with the forefinger, though naturally there are no limitations as to the exact manner of operation chosen by the user.

From the foregoing description and a study of the drawing it will be seen that I have thus provided a simply constructed and very quickly and easily operated hacksaw frame which will hold saws of any length, within reasonable limits, with absolute firmness and security. It will be noted that the saw blade may be placed in a plane with the back or at right angles thereto, with the saw teeth facing in a selected direction, there being four possible positions and, if desired, the blade may be reversed to cut on a push stroke or a pull stroke. It is believed that the construction, operation and advantages will be readily apparent to one skilled in the art without further explanation.

While I have shown and described a preferred embodiment of the invention, it should be understood that the disclosure is merely an exemplification of the principles involved as it is conceivable that various changes might be made to widen the field of utility and increase the adaptability of the device, and I reserve the right to make all variations and modifications desired, provided they constitute no departure from the salient features of the invention or the scope of the subjoined claims.

What is claimed is:—

1. A hacksaw frame comprising a longitudinal back bar bent laterally at one end to constitute a handle, said handle having a forward extension at its free end, an adjustable front anchor member located at the front end of the back bar, a yoke straddling the latter and pivotally connected to the anchor member to allow the same to rock, a rearwardly extending heel piece carried by the said member bearing against the inner or under edge of the back bar when rocked, to hold the anchor member against rearward movement, means carried at the free end of the anchor member for detachable connection with a hacksaw blade, a lever pivoted to the handle to swing inwardly and rearwardly, said lever having an arm extending downwardly and provided with a rearward cam face, a pull bar slidably mounted in the handle extension and detachably connected to the blade at one end and engaging the rearward cam face of the cam arm at the other end to tension the blade when the lever is swung.

2. A hacksaw frame comprising a longitudinal back bar bent laterally at one end to constitute a handle, said handle having a forward extension at its free end, an adjustable front anchor member located at the front end of the back bar, a yoke straddling the latter and pivotally connected to the anchor member to allow the same to rock, a

- rearwardly extending heel piece carried by the anchor member and bearing against the inner or under edge of the back bar when rocked, to hold the anchor member against 5 rearward movement, means carried at the free end of the anchor member for detachable connection with a hacksaw blade, a swingable lever mounted in the forward extension of the handle, a guide box carried 10 by said extension, a pull bar slidably mounted in said box to move longitudinally of the frame, said bar having means at its forward end for detachable connection with a hacksaw blade and bifurcated at its rear end 15 where extending beyond the guide box, a roller mounted in the bifurcation, a cam arm carried by the lever to engage the roller and draw the pull bar rearwardly when the lever is gripped to the saw handle.
- 20 3. A hacksaw frame comprising a back bar having one end formed into a handle provided with a forward extension in spaced relation to the back bar, a guide box mounted on said extension, a front anchor member 25 slidably mounted on the front end of the back bar, the lower end of the anchor member having means for detachable connection to a saw blade, means for resisting rearward movement of the front anchor member when 30 pulling strain is imparted, an upstanding actuating lever pivoted at its lower end to the handle extension, a pull bar mounted in the guide box and extending forwardly and rearwardly of the same, the front end of 35 the bar having means for detachable connection to the saw blade and the rear end thereof being slotted, a roller mounted in said slot, the axis of the roller being below the pivot of the actuating lever, and a curved 40 cam arm carried by said lever and extending through the slot of the pull bar and engaging the roller, to pull the saw blade rearwardly and tension the same when the lever is gripped to the handle.
- 45 4. A hacksaw frame comprising an elongated back bar having one end formed into an offset handle provided with a forward extension at its free end in spaced relation to the back bar, a guide box mounted at the 50 front end and on one side of said extension, a front anchor member slidably mounted on the front end of the back bar, the lower end of the anchor member being in alignment with the said guide box and having 55 means for detachable connection to the front end of a saw blade, means for resisting rearward movement of the front anchor member when pulling strain is imparted through the saw blade, an upstanding, loop-shaped actuating lever pivoted at its lower end to the 60 side of the handle extension, the front side
- of the lever acting as a finger protector, a longitudinally slidable pull bar mounted in the guide box and extending forwardly and rearwardly of the same, the front end of the 65 bar having means for detachable connection to the rear end of the saw blade and the rear end thereof being vertically slotted, a roller mounted in said slot at the end of the bar, the horizontal axis of the roller being below 70 the pivot of the actuating lever, and a curved cam arm carried by the front side of said lever and extending down through the slot of the pull bar and engaging the front side of the roller, the rear roller-engaging edge of the said arm being curved and closer, at the lower free end of the arm, to the lever pivot than at its upper end, to pull the saw blade rearwardly and tension the same when the lever is gripped to 75 the handle and to lock said lever against the front side of the same by said tension.
5. A hacksaw frame comprising a back bar bent to form an offset handle at the rear end thereof, slidable means mounted on 80 the front end of the bar for connection with a saw blade, means for preventing rearward movement of the front saw holding means, a forward extension carried by the free end of the handle, a longitudinally slidable saw-engaging bar mounted on said extension, said bar having a roller at its rear end, an upstanding actuating lever located in advance of the saw handle and adapted to be gripped against the front side thereof, said 85 lever being pivoted at its lower end to said handle extension and above the axis of said roller, an eccentric arm carried by the lever and engaging the front side of the roller at all times, the rear edge of said arm being 90 such shape as to pull the roller and slidable bar rearwardly to tension the saw blade when the lever is gripped to the handle and to be automatically locked in such position 95 by the pull of the saw below the lever pivot.
6. A hacksaw frame comprising a back bar, a handle at one end of said back bar, an anchor bar extending from the opposite end of the back bar and carrying a saw-blade securing means, a hand guard pivoted upon 100 the end of the handle to swing up against the inner face of the handle, a downwardly-extending cam finger carried by the said guard and a saw-holding member provided with means for engagement with said cam 105 finger to thereby tension the saw when the guard is raised.

In testimony, that I claim the foregoing as my own, I have hereto affixed my signature.

CHESTER RAY HANNING.
